Primary Examiner — Eliza Z Harvey*Assistant Examiner* — Adrian A Shwaiko(57) **CLAIM**

The ornamental design for a fixed plate mount, as shown and described.

DESCRIPTION

FIG. 1 is a bottom, front and right side perspective view of a fixed plate mount, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a enlarged view of portion 9 in FIG. 1;

FIG. 10 is an enlarged view of portion 10 in FIG. 2; and,

FIG. 11 is a enlarged view of portion 11 in FIG. 2.

The evenly dashed broken lines illustrate features of the fixed plate mount that form no part of the claimed design. The unevenly dashed broken lines define the boundary of enlarged views and form no part of the claimed design.
